NEEDLE OR TUFTING DEVICE

Rudolph C. Lang, New York, N. Y., assignor to
 A. B. A. Specialties Company, Inc., New York,
 N. Y., a corporation of New York

Application June 15, 1932, Serial No. 617,375

5 Claims. (Cl. 223—38)

This invention relates to improvements in needles or tufting devices, and by that is meant needles which are to be used in tufting mattresses, day beds, upholstery and the like. This particular device is primarily adapted for the practice of the method and the use of the tufting elements disclosed in the copending application for patent filed by Annette Fridolph June 8, 1931, Serial Number 542,799.

10 An important characteristic of this method and of the tufting elements used in connection therewith resides in the use of a preformed tufting element which is placed in its final tufting position by one operation on the part of the tufting operator. The tufting element is provided with a head or similar means which is adapted to be received by the needle and within the needle, and when the needle is passed through the mattress, day bed or other article being tufted, this 20 head is released and the tufting operation is completed.

The principal object of this invention is the provision of a single one-piece form of needle which is readily adapted to use the tufting elements and practice the tufting process of the above mentioned Fridolph application.

To the accomplishment of the foregoing and such other objects as may hereinafter appear, this invention consists in the construction, combination and arrangement of parts hereinafter described and then sought to be defined in the appended claims, reference being had to the accompanying drawing forming a part hereof and which shows, merely for the purpose of illustrative disclosure, two embodiments of my invention, it being expressly understood, however, that various changes may be made in practice within the scope of the claims without digressing from my inventive idea.

40 In the drawing—

Figure 1 represents a perspective view of one form of needle constructed to embody my invention, one end of the tufting element being associated with the head of the needle.

45 Figure 2 is a longitudinal cross section of the head end of the needle shown in Figure 1 with positions of the tufting head indicated.

Figure 3 is a cross sectional view through a mattress or other article being tufted illustrating the use of this device.

50 Figure 4 is a perspective view of another form of needle embodying my invention.

Figure 5 is a longitudinal cross section of the head of the needle shown in Figure 4.

Figure 6 is a transverse cross section taken substantially on line 6—6 of Figure 1.

Figure 7 is a transverse cross section taken substantially on line 7—7 of Figure 4.

Figure 8 is a side elevation of another form of 60 needle embodying my invention.

The needle 1 is preferably in the form of an elongated metallic member having a sharp point 2 at one end. As it is adapted to be used for tufting mattresses, day beds, upholstery and the 65 like, the needle will preferably be made of heavy and strong material and should be solid in construction, though for certain purposes a tubular or hollow needle may be suitable and satisfactory.

The reference character 3 designates the head 70 end of the needle and this is shown as flattened and widened in construction. This head end is provided with the open trough or recess 4 for a substantial length along one side thereof, this trough or recess being of sufficient width to slidably and readily receive the head 5 of the tufting element 6. Entrance to this trough or recess 4 is obtained by means of the opening or aperture 7 on the other side of the head of the needle. This opening or aperture is of sufficient size to 75 permit the ready passage of the head 5 of the tufting element therethrough. This opening or aperture 7 is removed from the extreme end of the needle, and in fact gives entrance into the lower portion of the trough or recess 4 and leads 80 into a comparatively narrow slot 8 which extends upwardly therefrom to a point near the upper end of the needle. This slot 8 is of sufficient width to receive the body part of the tufting element 6 so that when the head 5 is introduced into the 85 trough or recess 4 by being passed through the opening or aperture 7 and the said head is moved upwardly until the body of the tufting element 6 is positioned in the narrow slot 8, the tufting head 5 will be securely locked and held in position within the head of the needle ready for the 90 tufting operation.

In performing the tufting operation, the head of the tufting element is placed in the recess 4 of the needle as described and the needle is then 100 forced through the mattress, day bed, upholstery or other article until the tufting element passes through the article as a whole. The tufting head is then readily released from the head of the needle and engages the surface of the article being tufted so that this particular tufting operation is completed. The needle may be passed from top to bottom, or bottom to top, or side to side through the article being tufted.

105 In the other form of device illustrated in Fig- 110

ures 4, 5 and 7, the needle 11 is of substantially the same construction having the sharp point 12 and the head end 13. This head end is flattened and widened in construction and has the closed end 14. Below the closed end 14 the needle is hollowed out or formed or provided with a trough or recess 15 forming a chamber or compartment which is adapted to receive the head 16 of a tufting element 17. In the form illustrated in the drawing, this tufting head 16 is flat, and therefore the trough or recess 15 is greater in width than in depth.

This trough or recess 15 is somewhat longer than the full length of the head 16 and a portion of the trough or recess is closed, except for a narrow slot 18, by means of the overhanging flange portions 19 of the body of the needle. These flange portions 19 form a top for a portion of the recess 15, and the slot 18 provides a means to receive the material forming the body of the tufting element 17.

In this form of device it is seen that the recess 15 is shaped to correspond with the shape of the head 16 of the tufting element and is large enough and wide enough to freely receive this head element, and furthermore, the distance between the closed end 14 and the edges of flanges 19 may be less than the length of the head 16 of the tufting element. Therefore, when the head of the tufting element is placed in the recess and pushed downwardly it will pass under the over-extending flanges 19 with the material of the body of the tufting element passing into the narrow slot 18 so that the head of the tufting element is securely locked in position within the head of the needle.

This tufting operation is exactly the same as with the other form of this invention previously described. The needle is passed through the mattress, day bed, upholstery or other article in any direction after the tufting element is connected to the needle as above described. The entire tufting element is pulled through the article being tufted and when the head of the needle passes the opposite surface from where it enters, the head 15 may be readily released from the needle and will engage the surface through which the needle has just emerged to complete the tufting operation.

It is to be noted that in both of the forms of this invention, that head of the tufting element which is passed through the article being tufted is positioned entirely within the head of the needle and is therefore carried completely through the article being tufted. In the form usually used, the tufting element has a similar or corresponding head on the other end which engages that surface of the article being tufted through which the point of the needle first passes and as the needle is drawn therethrough, this last mentioned head will engage such surface and anchor that end of the tufting element as a whole. The other end of the tufting element is anchored as previously described, after being released from the head of the tufting needle after the latter has passed completely through the article being tufted.

The tufting element for which this device is particularly designed includes a length of flexible material such as tape or the like, forming the body thereof with a stiffened head on each end thereof. This head may take various forms, one preferred form being shown in the drawing. This form of head is comparatively wide and flat and the head end of the needle is so formed

that the sides of the trough or recess in which the tufting head fits are rounded or otherwise shaped so as to receive the tufting head in a fairly tight fit, resulting in the secure holding of the tufting head within the head of the needle until it is desired to release the same at the end of the tufting operation.

In the construction shown in Figure 8, the recess for receiving the tufting head of the tufting element is located adjacent the point of the needle, the needle being designated by the reference character 20, the trough or recess 21, the narrow slot 22 providing the overhanging flange portions 23 for the trough or recess 21 whereby the tufting head of the tufting element is securely locked and held in position during the tufting operation.

It is therefore seen that I have provided a device of simple and unitary construction, which is very simple to use and which will handle and control and use the tufting elements referred to very efficiently and in a secure manner and perform a very satisfactory tufting operation.

What I claim is:

1. A tufting needle or the like having a head formed with a trough or recess to slidably receive a stiff tufting head of a preformed tufting element, said needle head also having an opening leading to said trough or recess, said opening being longer in length than the maximum width of said head so as to receive a tufting head longer than such maximum width, and a restricted slot communicating with said opening and said trough or recess and adapted to receive part of the body of the tufting element and securely hold the tufting head within the trough or recess of the needle head during the tufting operation.

2. A tufting needle or the like having a sharp point at one end and a head at the other end, said head being hollowed out to form a chamber to receive a stiff tufting head of a preformed tufting element, said needle head having a cut out portion to form an opening leading to said chamber to permit the insertion of the tufting head, said needle head also having a restricted slot communicating with said chamber and said opening to receive part of the body of the tufting element and encase and hold the tufting head within the chamber in the needle head during the tufting operation.

3. A tufting needle or the like having a sharp point at one end and a head at the other end, said head being hollowed out to form a chamber to receive the tufting head of a tufting element, said needle head having an opening leading to said chamber to permit the insertion of the tufting head, said needle head also having a restricted slot formed by bent over flange portions on the needle head, said slot communicating with said chamber and with said opening to receive part of the body of the tufting element and hold the tufting head within the needle head during the tufting operation, the chamber in said needle head being adapted to have the tufting head positioned entirely within said needle head.

4. A tufting needle or the like having a sharp point at one end and a head at the other end, said head being hollow for receiving a stiff tufting head of a preformed tufting element, said needle head having a cut away portion forming an opening for the insertion of the tufting head, said needle head also having a relatively narrow slot communicating with said opening to receive part of the body of the tufting element and to

securely hold the tufting head within said needle head during the tufting operation.

5. A tufting needle having a sharp point at one end and a head at the other end, said head having an imperforate bottom face and upstanding opposite sides and the front face of the head cut away at one portion thereof to form a channel section to permit insertion of a tufting head on a tufting element, and the front face adjacent the cut away portion forming a chamber with the bottom face and sides and being provided with a restricted slot for securely holding a tufting head in position during the tufting operation. 80
